UNITED STATES PATENT OFFICE

STANLEY M. WRIGHT AND ANDREW D. McGILL, OF DENVER, COLORADO

DESIGN FOR A FISH LURE

Application filed August 22, 1929. Serial No. 32,512. Term of patent 14 years.

To all whom it may concern:

Be it known that we, STANLEY M. WRIGHT and ANDREW D. McGILL, both citizens of the United States, residing at Denver, in the county of Denver and State of Colorado, have invented a new, original, and ornamental Design for Fish Lures, of which the following is a specification, reference being had to the accompanying drawing, forming a part hereof.

In the drawing:

Fig. 1 is a front elevation of the fish lure showing our new design.

Fig. 2 is a side elevation thereof.

We claim:

The ornamental design for a fish lure as shown.

STANLEY M. WRIGHT.
ANDREW D. McGILL.
